UNITED STATES PATENT OFFICE

GEORGE A. A. GILLEN, OF JERSEY CITY, NEW JERSEY

RAILWAY BRAKE APPLIANCE

Application filed July 8, 1930. Serial No. 466,550.

This invention relates to new and useful improvements in railway brake appliances, and more particularly it pertains to improvements in freight car braking apparatus.

5 Freight car braking equipment as commonly constructed includes an element generally known as a retainer valve. These retainer valves require adjustment after each braking operation before the engineer can 10 recharge the train line pressure to again apply the brake, and these adjustments require the constant attention of the train crew, which on a fast train or in bad weather, is attended by many hazards.

15 It is one of the objects of the present invention to provide means in the air brake system of a freight train, whereby, the aforementioned operation of adjusting the several retainer valves as well as the valves 20 themselves, may be entirely eliminated.

It is another object of the invention to provide novel means whereby the engineer may have full control of the recharging of the train line pressure, thereby giving to the 25 engineer, complete braking control of a train.

It is another object of the invention to provide novel means whereby the engineer may tell at all times the amount of air pressure 30 in the brake cylinders, and by which he may vary or adjust the pressure in the brake cylinders of the system.

Other objects of the invention reside in certain novel and improved constructions, arrangements and combinations of parts hereinafter described and particularly pointed out in the claim, the advantages of which will be readily understood and appreciated by those skilled in the art.

40 The invention will be clearly understood from the accompanying drawings illustrating the invention in its preferred form and the following detailed description of the constructions therein shown.

45 In the drawings,

Figure 1 is a perspective view of a portion of a freight train, showing the same equipped with a device in accordance with the present invention, the latter being illustrated 50 diagrammatically,

Figure 2 is a view partly in elevation and partly in section of the control valve of the present invention, and;

Figure 3 is a diagrammatic view illustrating the device of the present invention 55 and its relation to the elements of an air brake system.

Referring specifically to the drawings, and particularly to Figure 2 thereof, it will be seen that a device constructed in accordance 60 with the present invention comprises a chamber 10, having connected thereto an air inlet pipe 11, and an air exhaust or outlet pipe 12. The chamber 10 is preferably cylindrical in shape, and the inlet and outlet pipes 65 are connected preferably in the ends thereof. Projecting from the cylindrical chamber, there is a flange or the like 13 provided with openings 14, by which the chamber may be secured in operative position in the cab of 70 a locomotive, adjacent the engineer's station therein.

The chamber 10 has a partition 15 arranged preferably adjacent its outlet end, 75 and said partition has a passage 16 therethrough. Mounted in the partition 15, and adapted to open and close the passage 16, there is a valve 17 which has a port 18 extending therethrough adapted when in registration with the port 16, to exhaust the main portion of the chamber 10. The valve 17 has an operating handle 19, and an index pointer 20 which co-incides with calibrations 21 to indicate the position of the valve passage 18 relative to the passage 16 of the partition 15. A gauge 22 is suitably mounted 80 upon the chamber 10, and has communication with the interior thereof to give a reading of the pressure within the chamber between the inlet end thereof and the partition 15.

As illustrated in Figures 1 and 3 the chamber 10 is mounted in a locomotive cab, and its intake pipe 11 is connected by a pipe 30 85 to the brake cylinder pressure line pipe 31 which is connected to the exhaust ports of the triple valves 33', on the several cars by pipes 35 while the train line 32 is likewise connected to the auxiliary reservoirs by a pipe connection 33, the auxiliary reservoir 34 90

being connected to the brake cylinder 36 by a pipe 37. The brake cylinder pressure pipe 31 and train line pipe 32 on the several cars are connected by short hose lengths 38 and 5 39 respectively, and the usual cut out cocks 40 and coupling 41 are provided.

The device operates in the following manner:

The brakes are applied in the usual manner by the engineer. When it is desired to 10 release the brakes, the valve 17 which is normally closed is moved to position where its passage 18 is in alignment with the passage 16, releasing the air in the brake cylinders 15 and thus releasing the brakes. Furthermore, by proper operation of the valve 17 the engineer may regulate the pressure retained in the brake cylinders as desired.

In installing the device, it is to be understood 20 that the brake cylinder pressure pipe 31 is connected to the exhaust ports of the several triple valves by the pipes 35. Also it is to be understood that the several cut out cocks of the train line are open except the 25 cock at the front of the locomotive, and the remote cock on the last car of the train.

From the foregoing, it will be apparent 30 that the present invention provides an attachment for air brake systems, the use of which eliminates the necessity of retainer valves, and the several adjusting operations attendant the use thereof. Furthermore, the invention provides a device, the use of which gives to the engineer complete control of the 35 braking operation of a train, and at the same

time, the device gives the engineer absolute control of his brake cylinder pressure.

Having thus described the invention, what I claim as new and desire to secure by U. S. Letters-Patent, is:

Means for controlling the pressure in an air pressure conduit comprising a cylinder having one end connected to one end of the conduit, a partition in the cylinder adjacent the other end and dividing the cylinder into a large chamber and a small chamber, an exhaust pipe connected to said other end of the cylinder in communication with the small chamber, a pressure gauge mounted on the cylinder and in communication with the large chamber, a flange on the exterior of the cylinder for attachment to a supporting member, said partition having a passage extending therethrough for connecting the two chambers together, and a vertically arranged tapered passage intersecting the first passage and having its large end extending out through the top of the cylinder, a tapered valve member fitting in the tapered passage and having a port therein for registering with the first passage when the valve is turned to a certain position, a handle connected to the upper end of the valve, and the lower end of the valve having a threaded shank passing through a hole in a part of the cylinder and a nut threaded on the shank for holding the valve in the tapered passage.

In testimony whereof I affix my signature.

GEORGE A. A. GILLEN.
